Lock, Kehlenbeck & Mathe

UNITED STATES PATENT OFFICE.

RAMÓN M. RODRIGUEZ, OF NEW YORK, N. Y.

VANITY CASE.

Application filed February 10, 1923. Serial No. 618,222.

To all whom it may concern:

Be it known that I, RAMÓN M. RODRIGUEZ, a citizen of the United States, and resident of the borough of Manhattan, city, county, and State of New York, have invented certain new and useful Improvements in Vanity Cases, of which the following is a specification.

My invention relates to vanity cases of the type commonly carried about by ladies and has for its object to provide a vanity case adapted to contain a plurality of cosmetics and including a mirror and constructed in a manner adapting all of the cosmetics and 15 the mirror to be exposed for use simultaneously.

Reference is to be had to the accompanying drawing which illustrates an example of the invention without defining its limits and 20 in which Fig. 1 is a plan view of the vanity case; Fig. 2 is a side view thereof partly in section; Fig. 3 is a plan view showing the vanity case extended for use and Fig. 4 is a side view of Fig. 3 with parts in section.

As shown in the illustrated example the vanity case comprises a plurality of sections pivotally connected with each other so as to be capable of being moved to positions in linear alignment with each other to coincidentally expose the interiors of all of said sections; in the normal condition said sections are folded into superimposed registry in which they represent a compact unit readily carried in the purse or pocket. That 25 is to say the vanity case may consist of a main section 5 to which an auxiliary section 6 is pivoted at 7 in such a manner as to be pivotally movable in a plane parallel with the plane of the main section 5. A cover 30 section 8 is hinged at 9 to the main section 5 and is pivotally movable relatively thereto in a plane at right angles to the plane of the main section 5. In other words the auxiliary section 6 and the cover section 8 are 35 movable relatively to the main section 5 about axes which extend transversely to each other. In the illustrated example the main section 5 is provided with a compartment 10 adapted to contain rouge 11 and a second compartment 12 adapted to contain 40 a lip stick 13. The compartment 10 is of such depth as to permit a powder puff 14 to be placed therein as shown in Fig. 4; in such case it is preferred to provide a hinged 45 clamping member 15 adapted to extend

across said compartment 10 to hold the powder puff 14 therein; said member 15 being movable to an inoperative position as shown in Fig. 3 to permit the removal of said powder puff when the latter is desired for 50 use. It will be understood that the hinge of the member 15 is a spring hinge operating to maintain the member 15 normally in the position indicated by dotted lines in Fig. 3. To permit the ready removal of the lip 55 stick 13 the compartment 12 may be provided with a recess 16 into which the tip of the finger may be inserted. The auxiliary section 6 is provided with a compartment 17 adapted to contain face powder 70 18 as shown in Fig. 3. The cover section 8 includes an interior mirror 19 as also shown in said Fig. 3.

In its normal condition the sections of the vanity case are folded upon each other 75 as shown in Figs. 1 and 2 in which the cover section extends over the auxiliary section and locks all of the sections in this position; to automatically align the auxiliary section 6 in superimposed registry with the main section 5 a shoulder 20 may be provided upon the periphery of said section 6 for engagement with the hinge 9. In its normal condition the vanity case represents a unit 80 of small dimensions and compact form 85 easily carried about. When it is desired to use one or all of the cosmetics the sections are adjusted to the positions shown in Fig. 3 in which all of said sections are in linear alignment with each other; in this condition the rouge 11, lip stick 13, face powder 18 and mirror 19 are concurrently exposed and are so located with respect to each other as to make each and every one of the cosmetics easily accessible. In this position 90 the main section 5 may be held in the hand with one of the fingers serving to incline the cover section 8 to position the mirror 9 properly for facilitating the application 95 of the cosmetics. With the described construction it is unnecessary to reverse the vanity case when it is desired to use one cosmetic or the other and furthermore it is necessary to manipulate only one cover section to render all of the cosmetics easily 100 accessible for use. It will be understood that in some cases the compartments 10 and 12 and 17 may be otherwise located with respect to the sections than in the illustrated 105 example; that is to say the compartments 10 110

and 12 may be located on the section 6 and the compartment 17 located on the section 5 if desired.

Various changes in the specific form 5 shown and described may be made within the scope of the claims without departing from the spirit of the invention.

I claim:

1. A vanity case comprising a main section containing a cosmetic, an auxiliary section pivoted to said main section and containing a cosmetic and a cover section including an interior mirror pivoted to said main section at a point diametrically opposed to the pivot of said auxiliary section, said sections being movable to positions in linear alignment with each other to coincidentally expose said cosmetics and mirror for use, and to folded positions in registry with each other, said cover section co-operating with the auxiliary section to maintain all of said sections in their folded positions.
2. A vanity case comprising a main section provided with compartments adapted

to contain rouge and a lip stick respectively, 25 a hinged clamping member on said main section adapted to extend across one of said compartments, an auxiliary section pivoted upon said main section and having a compartment for face powder, said auxiliary 30 section normally lying in registry with said main section and over the compartments thereof and being movable to an extended position in which the lip stick, rouge and face powder are simultaneously exposed for 35 use and a cover section hinged upon said main section and adapted to normally cover said auxiliary section and maintain all of said sections in superimposed registry, said cover including an interior mirror and being 40 movable to an extended, open position whereby said mirror is exposed for use coincidentally with said lip stick, rouge and face powder.

In testimony whereof I have hereby 45 signed this specification.

RAMÓN M. RODRIGUEZ.
